UNITED STATES PATENT OFFICE.

ISAAC MESEROLE, OF SPRINGVILLE, PENNSYLVANIA.

BUTTER-PAIL.

SPECIFICATION forming part of Letters Patent No. 296,034, dated April 1, 1884.

Application filed January 21, 1884. (No model.)

To all whom it may concern:

Be it known that I, ISAAC MESEROLE, a citizen of the United States, residing at Springville, in the county of Susquehanna and State 5 of Pennsylvania, have invented certain new and useful Improvements in Butter-Pails; and I do hereby declare the following to be a full, clear, and exact description of the invention, such as will enable others skilled in the art to which it appertains to make and use the same.

It has been found by experience that butter can be preserved in a good sweet condition much longer in a tin or metallic vessel than 15 in a wooden one; but one objection to the use of a tin vessel has been the difficulty in constructing a cheap, strong, durable, easily-adjusted air-tight cover, and the object of my invention is to remedy that difficulty.

20 It consists in the combination of a wooden lid and the metallic body and their means of attachment, as more fully hereinafter described and claimed.

My improvement is illustrated in the accompanying drawings, in which Figure 1 is a 25 plan view, Fig. 2 an elevation, and Fig. 3 a detached view, of a part of the device.

In the drawings, A is the body of the pail or vessel, made of tin; and B, the wooden cover. 30 The cover is provided with cleats c c', of the usual form. It is also provided on its upper surface with lugs d' d' d'', having inclined faces. These lugs I preferably make of metal, with prongs at their ends, which are driven 35 into and through the lid and are clinched on its under side.

D are hooks attached to the body of the vessel, and extending upward and over the edge of the cover in such a manner as to permit the 40 lugs d' to be slid thereunder, the hooks riding up the inclined faces of the lugs. Said hooks

are metal rods bent into the required shape and soldered or otherwise secured to the body of the vessel.

E is a swinging latch attached to the eye of 45 a rod, f, secured to the body of the package. Latch E rides upon the inclined face of lug d'', and is engaged by the teeth of a rack, G, secured to the cleat c'. The rack G (shown in Fig. 3) is inclined slightly in a direction opposite to the inclination of lug d''. In place 50 of the rack-bar, shown extending out from the cleat, a rack may be formed in the cleat.

In operation the cover is put on by first 55 sliding the lugs d' under the hooks D. The latch E is then raised, placed on and forced up the incline of the lug d'', and the end of the latch made to engage with teeth on the rack G. By these means the cover may be quickly pressed down very tightly on the vessel, making the package practically air-tight.

Having thus described my invention, what I claim, and desire to secure by Letters Patent, is—

1. The combination, in a butter or other 65 package, of the metallic body and wooden cover, the body provided with hooks and a latch and the cover with the inclined lugs and rack, substantially as and for the purpose described.

2. The cover of a package provided with 70 a cleat and rack and a bearing, such as d'', in combination with the body provided with a suitable latch adapted to engage with said rack, substantially as described.

In testimony whereof I affix my signature in presence of two witnesses.

ISAAC MESEROLE.
